UNITED STATES PATENT OFFICE.

CHARLES F. MORTZ, OF MONACA, PENNSYLVANIA, ASSIGNEE TO PHOENIX GLAS COMPANY, OF PITTSBURGH, PENNSYLVANIA, A CORPORATION OF WEST VIRGINIA.

SAND-BLAST MACHINE.

1,081,547.

Specification of Letters Patent. Patented Dec. 16, 1913.

Application filed February 10, 1913. Serial No. 747,365.

To all whom it may concern:

Be it known that I, CHARLES F. MORTZ, a citizen of the United States, and resident of Monaca, in the county of Beaver and State of Pennsylvania, have invented a new and useful Improvement in Sand-Blast Machines; and I do hereby declare the following to be a full, clear, and exact description thereof.

10 My invention relates to sand-blast machines.

The object of my invention is to provide a machine of this character in which the article to be sand blasted, such as a boulevard globe, is mounted in position outside of the box or receptacle containing the sand and the sand-blast nozzle, so that the globe, or other article, is entirely exposed to view, enabling the operator to examine the globe 15 to see whether the article has been properly sand blasted without the necessity of opening the receptacle, and at the same time making it possible to adjust the globe in position or remove it therefrom without the necessity of opening the receptacle.

To these ends my invention comprises, generally stated, a suitable receptacle containing the sand, a sand blasting nozzle contained within said receptacle, means for directing the sand from said nozzle, a supporting plate or cover for said receptacle having an opening therein, and means for supporting the article to be sand blasted in position on said plate over said opening, 20 said nozzle directing the sand through the opening into the interior of said article supported in this manner.

In the accompanying drawing, Figure 1 is a vertical section; Fig. 2 is a plan view; 25 Fig. 3 is a rear view; Fig. 4 is a section transverse to Fig. 1; and Fig. 5 is a modified form of ware-holder.

In the drawing the numeral 2 designates a suitable stand or frame which supports 30 the receptacle 3 containing the sand 4. This receptacle 3 has the conical bottom 5. The stand 2 has the brackets 6 arranged at intervals at the upper end thereof and said brackets support the idle-rollers 7. Resting 35 on the idle-rollers 7 is the supporting plate or cover 8. This plate 8 has the circular rack 9 at its outer edge. A Z-bar 10 connects the depressed portion 11 of the cover 8 with the main portion and said depressed portion is provided with the opening 12

which is surrounded by the flange 13. This flange 13 forms a support for the ring 14. This ring 14 may be held in place by the buttons 15. The ring 14 has the shoulder 16 upon which the globe 17 rests when in 40 position for sand-blasting. The ring 14 can be readily replaced by other rings having openings of different sizes so that the machine is made readily adaptable for all sizes of globes.

45 Mounted in the bracket 18 secured to the support or stand 2 is the clutch-member 19. A pin-wheel 20 on the clutch-member 19 engages the annular rack 9 of the supporting plate 8. A pulley 21 on the shaft 23 50 is connected up by the belt 26 to a suitable overhead pulley. A pin-wheel 27 on the shaft 23 meshes with the pin-wheel 28 on the shaft 29. A crank-arm 30 is connected to the shaft 29 and said crank-arm is connected to the rod 31. The inner end of this rod 31 is connected to the arm 32, said arm being connected to the air-pipe 33 which is screwed into the T-connection of the pipe 34 leading from a fan or other source of 55 supply. The sand-pipe 40 connected to the nozzle is embedded in the sand and has the opening 41 for the admission of the sand, the free end of said pipe being bent upwardly and projecting above the sand so as 60 to admit air.

65 The power-shaft 42 is connected up to any suitable source of power and said shaft is provided with the clutch-member 43 which is adapted to engage the clutch-member 19. 70 A spring 44 is interposed between a collar 45 on the shaft 42 and a yoke 46, said spring tending to throw the clutch-member 43 into engagement with the clutch-member 19. A rod 47 is connected up to the yoke 46 and 75 said rod extends down to the treadle 48, so that by the operation of said treadle the clutch-member 43 is released from the clutch-member 19.

80 A valve 49 is provided in the pipe 34 and 85 said valve is closed by the operation of the treadle 48, said treadle having the link 50 which is connected up to the arm 51 of the valve. The spring 52 is connected to the bracket 53 and to the arm 51, said spring 90 acting to normally open said valve 49.

95 In the operation of my improved sand-blast machine the operator places a globe 17 in position on the ring 14 and then removes his foot from the treadle 48. The spring 100 105

throws the clutch 43 into engagement with the clutch 19 and a rotary motion is imparted to the pin-wheel 20, which in turn imparts a rotary movement to the supporting plate carrying the globe to be sand-blasted. At the same time through the connections described, a reciprocating motion is imparted to the rod 31 and the nozzle 36 is tilted up and down to change the direction 10 of the sand-blast. At the same time that the operator removed his foot from the treadle 48 the spring 52 opened the valve 49 and the air was forced through the pipe 33 and sucked in the sand from the pipe 40 so as to 15 discharge it through the nozzle 36. The nozzle 36 being directed up through the opening in the ring 14 directs the sand against the interior of the globe, and as the globe is rotating the sand is swirled around 20 acting on all parts of the interior of the globe, so that an even and uniform action of the sand-blast is obtained. Moreover by having the globe entirely exposed to view the operator is able to tell when the globe 25 has been properly sand-blasted and it is not necessary to open the receptacle to examine the article as has been the case heretofore. Articles of different sizes may be taken care of and as the rings 14 are readily removable, 30 no time is lost in this operation.

In Fig. 5 I have shown a shade of oblong form with open ends in which the shade is held at the top by the spring cap-piece 66. This cap-piece is mounted on a standard 60 35 on the supporting ring 14. A spring 61 normally holds the cap in engagement with the top of the shade. The machine as shown in Fig. 1 is provided with an arm 62 fulcrumed

at 63, one end of said arm being provided with a swivel 64 adapted to engage the rod 40 65 on the cap-piece 66. The other end of the arm 62 is connected to the rod 67 connected to the treadle 48. By putting his foot on the treadle the operator releases the cap-piece to remove the ware and at the same 45 time cuts off the blast and stops the machine. What I claim is:

1. In a sand-blast machine, the combination of a suitable receptacle, a rotary cover-plate for said receptacle having an opening 50 therein, and forming a support for the article to be sand-blasted, and means within said receptacle for directing the sand through said opening into said article.

2. In a sand-blast machine, the combination of a suitable receptacle, a rotary plate forming a cover for same having an opening 55 therein and forming a support for the article to be sand-blasted, a nozzle within said receptacle, and means for directing the sand- 60 blast through said nozzle into said article.

3. In a sand-blast machine, the combination of a suitable receptacle, a rotary plate forming a cover for same, a centrally located freely movable plate having an opening 65 therein and forming a support for the article to be sand-blasted, and means within said receptacle for directing the sand-blast through said opening into said article.

In testimony whereof I, the said CHARLES 70 F. Motz, have hereunto set my hand.

CHARLES F. MOTZ.
